UNITED STATES PATENT OFFICE.

ROBERT MIEHLE, OF CHICAGO, ILLINOIS.

COUNTING-MACHINE.

SPECIFICATION forming part of Letters Patent No. 593,773, dated November 16, 1897.

Application filed January 23, 1897. Serial No. 620,392. (No model.)

To all whom it may concern:

Be it known that I, ROBERT MIEHLE, a citizen of the United States, residing at Chicago, in the county of Cook and State of Illinois, 5 have invented certain new and useful Improvements in Counting-Machines, of which the following is a full, clear, and exact specification.

My invention relates to that class of counting-machines or registers for indicating the impressions made on printing-presses or the number of operations or movements of other forms of machinery or their parts; and it has more especial reference to that type of counting-machines in which are employed a series 10 of disks, which for convenience may be termed "digit-disks," bearing on their peripheries the nine digits and one cipher, and means revolving in unison with such disks 15 and actuated to impart the movement of one disk to the next succeeding disk in the series.

One of the objects of my invention is to provide a counting-machine comprising the minimum number of simple parts which shall 20 be of such form and arrangement as to greatly reduce the cost of manufacture and the liability of the machine getting out of order.

A further object of my invention is to so construct and arrange the parts as to enable 25 the use of coil-springs wherever a spring or cushion is desired, and thus avoid the serious defect heretofore existing in counting-machines due to the blade-springs employed losing their flexibility or form after being in 30 use a comparatively short time.

Another object of my invention is to impart the movement of one digit disk or wheel to the next succeeding one through the intermediary of positive means as contradistinguished from springs, and, further, to so multiply or gradually increase throughout the 35 series the initial movement of the first of such means in the series that the last such means shall have the same movement as the first, or at least a sufficient movement to enable it to engage and operate the next disk, notwithstanding the lost motion in bringing the engaging surfaces of the said means into contact.

With these ends in view my invention consists in certain features of novelty in the construction, combination, and arrangement of

parts whereby the said objects and certain minor objects hereinafter appearing are attained, all as fully explained with reference 55 to the accompanying drawings, and more particularly pointed out in the claims.

In the said drawings, Figure 1 is a front elevation of my improved counting-machine, showing a part of the casing broken away. 60 Fig. 2 is an end elevation thereof. Fig. 3 is an end view of the opposite end to Fig. 2. Fig. 4 is a detail plan section, hereinafter described. Fig. 5 is a vertical transverse sectional view taken on the line 5 5, Fig. 1. Fig. 65 6 is a similar section taken on the line 6 6, Fig. 1. Fig. 7 is a side elevation of one of the digit-disks. Fig. 8 is a sectional view of such digit-disk, taken on the line 8 8, Fig. 7, also illustrating the relation of such disk to 70 two of the others. Fig. 9 is a diagrammatic view of the levers which impart the movement of one disk to the other, showing them in their normal position; and Fig. 10 is a similar view showing the levers in their 75 engaging position.

The operating parts of my improved counting-machine are preferably arranged within a closed casing 1, which also serves as a support for the main shaft or pintle 2, mounted 80 in the ends of the casing 1. Arranged loosely on this shaft or pintle 2 within the casing is the series of disks 3 4 5 6 7, each of which represents the nine digits and one cipher and which for the sake of convenience I have 85 herein termed the "digit-disks." Any number of these disks may of course be employed, according to the capacity of the machine desired, and each is preferably provided around its periphery with a widened band or flange 90 upon which the nine digits and cipher are indicated, so that by forming openings 8 in the casing opposite each disk the progress of the registration may be observed.

The digit-disks are independent of each 95 other and revolve loosely upon the shaft 2, and each is provided with an extended hub or boss 9, which abuts against the hub or boss on the adjacent disk, and thus holds the disks the requisite distance asunder. Each of the 100 disks on one side is provided with a series of lugs or teeth 10, which are ten in number and correspond in relation and arrangement to the characters or numbers on the periphery

of the disk and which serve as means whereby motion or intermittent rotation is imparted to the disks to bring their numbers or characters successively opposite the openings 8 in the casing. Motion is imparted to the units-disk, which is of course the first one in the series on the right, by a pawl 11, which is of sufficient length to rest normally upon one of the lugs or teeth 10 of the units-disk and 10 to be permanently in position for engaging with the next one of such lugs when the pawl is advanced, the end of the pawl being preferably notched or curved, as indicated in Fig. 5, so as to avoid slipping out of engagement 15 with the tooth or lug 10. Arranged under the series of lugs 10 on each of the digit-disks is a combined holding-dog and alining-cam 12, pivoted upon a cross-pin 13, mounted in the ends of the casing 1 and each provided 20 with a wedge-shaped or double-beveled cam 14, whose apex is adapted to engage between each pair of the lugs 10 as the disks are rotated. These combined holding dogs and cams 12 14 are each provided on their under 25 side with a pin 15, inserted in the upper end of a coil-spring 16, whose lower end is socketed in a perforation 17, formed in a plate 18, resting upon the bottom of the casing 1 and being held in place by the simple means consisting of a lug 19 at each end passing through 30 an aperture in each end wall of the casing and held in place by the front plate 20, which is itself removably secured in place by a pin 21, passing through the ends of the casing 35 and through perforated ears 22, formed on each end of the inner face of the plate 20. By means of this pawl 11 and the double-inclined alining cam 14 it will be seen that when sufficient movement has been imparted to 40 either of the digit-disks to cause one of the pins or lugs 10 to pass over the apex of the cam 14 the incline on the other side of the cam under the influence of the spring 16 will continue the rotation of the disk until the 45 apex of the cam is midway between the two lugs bearing against the inclined surfaces and at such time the proper digit or cipher will be directly opposite one of the openings 8 in the casing and alined with the others on the 50 succeeding disks. The advantage of this, it will be seen, is that it is not necessary that the movement of the pawl 11 be gaged to a nicety so long as it is sufficient to push the lug or tooth 10 over the apex of the cam 14, 55 and in adapting the machine to universal use on diverse forms of machinery this feature is a great desideratum and cannot fail to be appreciated when it is taken into consideration that the moving parts in the various forms 60 of machinery to which the counting-machine may be attached will vary widely in their extent or degree of movement, and consequently great annoyance and difficulty would arise should it be necessary to depend upon 65 the movement of the pawl 11 for the requisite and entire movement of the digit-disk.

The heel of the pawl 11 is provided with a

perforation into which is inserted a pivot-pin 23, formed on or secured to the inner side of one end of a lever 24 and projecting through 70 a slot or opening 25, formed in one end wall of the casing 1. The pawl 11 is sleeved loosely upon the pin 23, and it is held from inward movement or from slipping off such pin by the face of the disk 3, as will be understood 75 from Figs. 1 and 3, and it is prevented from rising sufficiently far to slip over the periphery of the disk by the top of the casing. The outer side of the pawl 11 is provided with a pin or lug 26, to which is attached one end of 80 a coil-spring 27, whose other end is connected to a lug or hook 28, formed on the upper side of the arm 24, thus holding the pawl normally down in engagement with the teeth or lugs 10. The arm 24 is provided with a squared 85 or angular boss 29, (shown in dotted lines in Fig. 3,) which is pierced by a protruding end of the shaft 2 and upon which shaft the arm 24 oscillates. This angular boss 29 forms the means of attachment of the actuating-arm 30, 90 whose hub 31 is slipped over the boss 29 and held against displacement by a collar 32, secured to the end of the shaft 2 by a set-screw 33 or other suitable device, the arm 30 being provided with a series of perforations 31¹, 95 whereby it may be attached to the part of the machine whose movements it is desired to count or register. In order that the pawl 11 may be returned to its normal position and the arm 30 raised without depending upon the 100 return movement of the part of the machinery to which the arm is connected, one end of the lever 24 is provided with an inwardly-projecting pin 34, upon which is pivoted the upper end of a rod 35, passing through a coil-spring 36 and having a shoulder 37 bearing against the upper end of such spring, while the lower end of the latter passes through a 105 perforated ear 38, formed on one end of the face-plate 20 and through which ear the rod 35 passes, as clearly indicated in Figs. 1 and 3, so that when the arm 30 is depressed the spring 36 will be compressed, and when the pressure upon the arm 30 is released the spring 110 will return such arm and the pawl 11 to their 115 normal positions. The lever 24, ear 38, and rod 35 are so disposed that the leverage of the end of the lever 24, which effects the compression of the spring 36, will gradually increase with the downward movement of the 120 arm 30, and the resistance of the spring 36 to the downward movement of such arm 30 will consequently be uniform substantially throughout the entire stroke of the arm 30 and thus avoiding the necessity for employing 125 a very strong spring in order to get the requisite tension at the final end of the return stroke.

Each of the digit-disks is provided with an aperture 39 and upon one side with a pair of 130 bosses 40. Arranged between and pivoted to the bosses 40 on the units-disk 3 is a lever 41, whose end opposite the opening 39 is provided with a lateral projection 42, which pro-

trudes through the opening and extends from the right-hand side of the disk or toward the adjacent end of the casing, while the opposite side of such lever 41 is provided with a projecting edge 43. Secured to the end of the casing 1 is a stationary cam 44, which is arranged in the path or line of rotation of the projection 42, and with the inclined face of which the inclined edge of the projection 42 engages at each complete rotation of the units-disk, and thus forces the edge 43 of the lever 41 to the left and causes it to engage with one of the pins or lugs 10 on the next disk 4, which is the tens-disk. At the ninth stroke of the pawl 11 the projection 42 is carried over or opposite the flat surface 44^a of the cam 44, and while in this position the edge 43 is in engagement with one of the pins on the disk 4. When the pawl 11 makes its next stroke, the projection 42 will be carried across the flat face 44^a without permitting the projection 42 to recede to its normal position protruded to the right, and while so passing the face 44^a the edge 43 of the lever 41 will impart a tenth-rotation to the disk 4 and if the disks have been properly set will bring the first digit or number "1" opposite the opening 8 and in line with the cipher on the disk 3, which advances a tenth-rotation with the disk 4, and thus registers ten downward strokes of the arm 30. The cam 44 may be secured to the end of the casing 1 in any desired way; but I prefer to form such cam on a hub-like portion 45, through which the pin or pindle 2 passes. This hub 45 is provided with a tongue 46, which fits in a complementary slot formed through the edge of the end of the casing, as shown in Figs. 1, 3, and 5, and which tongue and slot hold the hub 45 and cam 44 from rotating on the pin 2. For the sake of greater strength the outer side of the tongue 46 may be provided with a lip 47, projecting downwardly against the face of the end of the casing and thus holding the tongue and hub 45 against inward movement. The boss or hub 9 of the disk 3 may, if desired, be let into the hub 45, as indicated in Figs. 1 and 5.

Between the lugs 40 and in the aperture 39 of each of the succeeding disks is pivoted a lever 48, (see Figs. 6, 7, and 8,) each of which is provided on one side with a projection 49, which extends laterally to the right through the opening 39 and on the other side with an edge 50, which is elongated in the plane of oscillation of the lever on which it is formed. The projection 49, however, is arranged nearer to the pivot of its lever than the outer extremity of the edge 50, and such projection 49 is preferably elongated transversely or substantially transversely of the edge 50. These projections 49 and edges 50 are the same on all of the levers 48, with the exception of the projection 49 on the tens-disk 4, whose edge 65 or surface is slightly rounded, as clearly indicated in Figs. 1 and 8. All of the levers 41 48 are held in their normal positions with

the projections 42 49 protruding from the right-hand side of their respective disks by means of coil-springs 51, interposed between 70 one end of each of the levers and the disk to which it is pivoted, the under or inner side of such end of the lever being provided with a pin or lug 52, entering one end of the spring 51, while the side of the disk is provided with 75 a countersink 53, in which the end of the spring is seated, and a central pin 54, which enters the spring.

The ends of the levers carrying the edges 43 50 are located directly opposite or under 80 the cipher on each disk, and in the use of the machine all of the ciphers are arranged in line opposite the openings 8 in the casing, and when so arranged they will be one-tenth of a rotation past or this side of the flat surface 85 44^a of the cam 44. Consequently when the beveled projection 42 reaches the cam 44 on the ninth stroke it will force the projection 42 to the left and cause the edge 43 to engage with one of the pins or lugs 10 of the units- 90 disk 3 and the next or tenth stroke will carry figure "1" on the latter disk, which is adjacent to the pin or lug 10 thus engaged, opposite the opening 8 in the casing. The disk 4 will thus receive a tenth-rotation at each complete rotation of the disk 3, and all of the other disks will remain at rest until the projection 49 on the disk 4 and the beveled projection 42 have arrived at a position in line with the plain surface 44^a of the cam 44, whereupon 95 such cam having forced the beveled projection 42 to the left and crowded the edge 43 against the projection 49 the lever carrying the projection 49 on the disk 4 will in turn crowd its edge 50 over into engagement with 100 the pin 10 corresponding to the figure "1" on the hundreds-disk 5, and as the arm 30 continues to descend the three disks 3 4 5 will rotate in unison as long as the beveled projection 42 is in engagement with the plain surface 44^a of 105 the cam 44, and in so rotating a tenth-rotation will be imparted to the hundreds-disk 5 as well as to the disks 3 and 4, and the numeral "1" on such disk will be brought down opposite the opening 8, thus registering one hundred 110 downstrokes of the arm 30. As soon as the beveled projection 42 has cleared the surface 44^a the springs 52 will return the levers 41 48 to their normal positions, and the levers will be free to rotate or revolve with their respective disks without engaging with any parts of the adjacent disks until another complete rotation of the units-disk has been accomplished, whereupon the edge 43, carried by that disk, being forced to the left at each 115 complete rotation, will successively engage with one of the pins or lugs 10 on the disk 4 and impart a tenth-rotation thereto without affecting any of the other disks until the projection 49, carried by the disk 4, and the projection 43 have again come into line with the cam 44, whereupon the next stroke of the pawl 11 will crowd the edge 50, carried by the disk 4, against the pin 10 corresponding to the nu- 120 125 130

meral "2" on the hundreds-disk 5, and thus impart a tenth-rotation to such latter disk, and as soon as the surface 44^a is cleared by the projection 42 the parts will resume their 5 normal position, as before explained, and the rotation of the two disks 3 and 4 will continue at the ratio of ten to one without molesting the disk 5, excepting at each tenth-rotation of the disk 4, and after the disk 5 has received 10 nine such partial rotations its projection 49 will have arrived at a position in line with the cam 44 and the projections 42 49, carried by the disks 3 and 4, and as the projection 43 rides up the cam 44 the edge 50, carried by the 15 disk 4, will be forced against the projection 49, carried by the disk 5, and consequently the edge 50, carried by the disk 5, will be projected between two of the pins carried by the next disk or thousands-disk 6, and as the arm 30 20 completes its downward stroke the beveled projection 42 will slide across the plain face 44^a of the cam 44 and the disk 6 will be compelled to rotate in unison with the disks 3, 4, and 5 for a tenth-rotation, or until the projection 42 is no longer crowded to the left by the cam 44.

Having thus described the operation of the device up to the thousands, the operation of the remaining disks will be readily understood, 30 and it will also be seen that the continued operation of the machine will eventually bring all of the ciphers together and opposite the openings in the casing 1; but should it be desired to reset the disks at an earlier 35 or any other stage any one of the disks from 4 up may be rotated in either direction by the thumb, and the units-disk may also be similarly rotated by raising the pawl 11 by means of the projecting pin 26.

40 The purpose of rounding or beveling one edge at least of the projection 49, carried by the tens-disk 4, it will be seen is to enable the projecting edge 43 of the tens-disk to engage therewith and force it inwardly or to the left 45 while the tens-disk is still moving, it being understood that should such edge be straight or squared, like the edges 49 50, carried on the succeeding disks, which come opposite each other before actual engagement, the edge 43, 50 carried by the units-disk, would hang on the projection 49 without deflecting the latter to the left. The corner of the edge 42 is beveled off to enable it to sooner start in between the pins 10 without engaging the wrong one. 55 It will also be seen that in order that the disks may be free to rotate without liability of frictional contact with each other or with any of the parts carried thereby it is necessary to have more or less lost motion or space between 60 the projection 49 on one lever and the edge 50, carried by the other lever, and that ordinarily this lost motion between the parts would entirely consume or take up the movement of the projecting edge 43 of the first lever or one carried by the units-disk, so that the movement imparted to the succeeding levers would be gradually decreased andulti-

mately become insufficient to project the edge 50 far enough to engage between the lugs or pins 10 on the succeeding disks. In order 70 that the movement of the first lever therefore may be multiplied upon the second and that of the second upon the third, and so on throughout the series, to a sufficient extent to compensate for the lost motion between the 75 engaging parts, I employ the described relation of the projections 49 and edges 43 50. The principle of this operation may be best understood from the diagrams shown in Figs. 9 and 10. In these figures I have designated 80 all of the projections on the right-hand sides of the levers 41 48 with the numeral 49 and all of the edges on the left-hand sides which engage with the pins 10 with the numeral 50 for the sake of convenience. In Fig. 9 the 85 first are shown in their normal position with a slight space between the projections 49 and edges 50, and in Fig. 10 they are shown in their engaged position or the position that each lever assumes when pushing its companion lever into a position for engagement with the pin or lug 10 on the next succeeding disk. When the first lever 41 is oscillated to the left, its edge 50 nearest its pivotal point or fulcrum will engage with the projection 95 49 on the next lever 48, and as the lever 41 continues to move to the left the projection 49 on the lever 48 and the edge 50 of the lever 41 will make relative movements which will bring the outer extremity of the 100 edge 50 against the projection 49, and in this way the long stroke produced by such outer extremity of the edge 50 will be imparted to the lever 48 at a point nearer to the fulcrum of the lever 48 than the engaging-point of the 105 edge 50 on the lever 41 is to the fulcrum of such lever 41. Hence the lever 41 will move farther at its outer end than does the outer end of the lever 41 after contact; but this additional movement is lost or broken up in the 110 space between the first and second levers 48, and consequently the movement of the first lever 48 after it touches the second lever 48 will be only equal to the movement of the lever 41 after the latter engages with the first 115 lever 48. Hence, while each lever in the series after the first receives from its companion a movement which is greater than the movement of such companion while in contact therewith, such increased movement, being 120 proportioned to the space between the levers, is consequently absorbed by said space, and as a result the increased movement is not manifested in the third lever from any given starting-point and all the levers move the 125 same distance.

The front of the casing 1 is provided with a hinged cover 51, which opens upwardly and in which the openings 8 are formed. This cover is provided with a fastening consisting 130 of a catch 52, which engages over a tooth 53 on one end of the cover, and adjacent to which tooth is formed a thumb-piece 54, by means of which the cover may be thrown upwardly,

the catch being simultaneously disengaged from the tooth 53 by a thumb-piece 55, formed on the catch 52, so that by one movement of the thumb the catch is disengaged and the cover raised. The catch is pivoted upon one end of the pin 21, which comes through the end of the casing 1, and the lower end of the catch is provided with a projection 56, between which and an ear 57, formed on the plate 20, is interposed a coil-spring 58, one end of the spring being let into the projection 56, while its other end surrounds a pin 59, formed on the inner face of the ear 57. The outward movement of the catch is limited and the spring 58 prevented from jumping out of place by a shoulder 60, formed on the catch and engaging on the top of the ear 57.

61 represents perforated flanges for convenience in attaching the machine to any suitable support, and 62 is an extended portion of the casing forming a hood over the slot 25 in the end of the casing for excluding dust.

The pivot-pins 40^a, which pivot the levers 41 48 between the lugs 40, are held in place at one end by the pintle or pin 2 and at the other end by a cross-pin 40^c, the lugs 40, as well as the hub or boss 9 of the disk, being bored straight through, as shown at 40^b in Fig. 7. Hence it will be seen that when the pin or pintle 2 is removed the pivot-pin 40^a may be driven out endwise by inserting an instrument in the outer end of the bore 40^b, the pin 40^c being slightly smaller than the bore 40^b, so as to leave a space for the passage of the punch or ejecting instrument.

Having thus described my invention, what I claim as new, and desire to secure by Letters Patent, is—

1. A counting-machine having in combination a series of digit-disks provided with teeth or lugs and each provided with an aperture therethrough, a stationary cam, a lever pivoted in each aperture of said disks and one of said levers having a projection adapted to engage with said cam on one side and an edge on the other side adapted to engage with said teeth or lugs of the next disk, and another one of said levers having a projection arranged within the circle described by said lugs and adapted to be engaged by said edge and means for imparting rotation to one of said disks, substantially as set forth.

2. A counting-machine having in combination a series of digit-disks each provided with an aperture and having teeth or lugs, a stationary cam, a lever pivoted in each of said apertures and one of said levers having on one side a projection adapted to engage with said cam on the other side, an edge adapted to engage with the teeth or lugs on the adjacent disk and also with the lever on the adjacent disk for crowding said levers against one another, substantially as set forth.

3. A counting-machine having in combination a series of digit-disks each provided with an opening therethrough and having teeth or lugs, a stationary cam, a lever pivoted in each

of said openings and one of said levers provided on one side with a projection adapted to engage with said cam and on the other side with an edge adapted to engage with the teeth or lugs of the adjacent disk and the others of said levers being each provided on one side with a projection and on the other side with an edge elongated toward its axis and in the plane of oscillation of the lever upon which it is formed, said levers being arranged adjacent to each other so that the said elongated edge on one will be opposite and adapted to engage with the said projection on the next, substantially as set forth.

4. A counting-machine having in combination a number of revolving oscillatory levers each provided on one side with an edge elongated toward its axis and in the plane of its oscillation and on the other side with a projection adapted to be engaged by the said elongated edge of the adjacent lever, rotary digit-disks having means for the engagement of said levers, and means for imparting rotation to one of said disks and oscillating said levers, substantially as set forth.

5. A counting-machine having in combination a number of revolving oscillatory levers each provided on one side with an edge elongated in the plane of its oscillation and on the other side with a projection elongated across the plane of such oscillation, said edge being arranged opposite and adapted to engage the projection on the adjacent lever, rotary digit-disks having means for the engagement of said levers, and means for revolving and oscillating one of said levers, substantially as set forth.

6. A counting-machine having in combination a number of revolving oscillatory levers each provided on one side with an edge elongated in the plane of its oscillation and on the other side with a projection whose outer margin is nearer the point of fulcrum of the lever than the outer extremity of said edge, said levers being arranged adjacent to each other so that the elongated edge on one will be opposite and adapted to engage with said projection on the next, rotary digit-disks having means for the engagement of said levers, and means for revolving and oscillating one of said levers, substantially as set forth.

7. A counting-machine having in combination a series of rotary digit-disks each having an opening or aperture therethrough and being provided with lugs or teeth, a lever pivoted in each of said openings and adapted to engage with said lugs or teeth and each lever having on one side an edge elongated toward its axis and in the plane of its oscillation and on the other side a projection with which the said edge of the adjacent lever engages, and means for periodically oscillating one of said levers, substantially as set forth.

8. A counting-machine having in combination a series of digit-disks, a stationary cam, a lever carried by one of said disks and having on one side a projection adapted to en-

gage with and be deflected by said cam, teeth or lugs carried by said disks, the other side of said lever being provided with an edge adapted to engage with said teeth or lugs on the 5 adjacent disk, a second lever carried by the adjacent one of said disks and being provided with an elongated projection adapted to be engaged by said edge on said first lever whereby the first lever will deflect the second lever

10 while the edge of the first lever is passing said projection, said second lever being also provided with a portion adapted to be projected into engagement with the teeth or lugs on the next succeeding disk and said next 15 succeeding disk being likewise provided with means with which said second lever engages and which in turn engages the teeth or lugs of the next or fourth disk; and means for imparting rotation to said first disk, substantially as set forth.

9. A counting-machine having in combination a series of digit-disks, a stationary cam, a lever carried by one of said disks and having on one side a projection adapted to en-

20 gage with and be deflected by said cam, teeth or lugs carried by said disk, the other side of said lever being provided with an edge adapted to engage with said teeth or lugs on the adjacent disk, a second lever carried by the

25 adjacent one of said disks and being provided with a rounded elongated projection adapted to be engaged by said edge on said first lever whereby the first lever will deflect the second lever while the edge of the first lever is pass-

30 ing said rounded projection, said second lever being also provided with a portion adapted to be projected into engagement with the teeth or lugs on the next succeeding disk and said next succeeding disk being likewise provided

35 with a lever having a projection adapted to be engaged by said second lever and a portion adapted to engage the teeth or lugs of the next or fourth disk, and means for imparting rotation to said first disk, substantially as set forth.

40 10. A counting-machine having in combination a series of digit-disks, pivoted levers carried by said disks and adapted to engage with each other, a fixed cam having the plain

45 face 44^a adapted to engage with one of said levers, said levers being provided with projections elongated in the direction of the length of said cam and also with elongated edges ext-

50 ending at an angle to said projections and in the plane of oscillation of the lever, means for rotating one of said disks and means whereby said levers are caused to rotate the remaining disks, said levers being arranged adjacent to each other so that the said elong-

55 ated edge on one will be opposite and adapted to engage with said elongated projection on the next, substantially as set forth.

60 11. A counting-machine having in combination a series of digit-disks each having an aperture therethrough, a non-elastic or rigid lever pivoted in each of said apertures, a coil-spring interposed between one end of each of

60 said levers and the disk to which it is pivoted, lugs or teeth on said disks, and means for rotating one of said disks and forcing said levers against each other and into engagement with said lugs, said levers being provided on one side with an edge elongated toward their axes and in the plane of their oscillation and on the opposite side with a projection elongated across such edge, substantially as set forth.

70 12. A counting-machine having in combination a series of digit-disks, a casing in which said disks are journaled, pivoted levers carried by said disks, the end of said casing being provided with a slot, a cam adapted to engage with one of said pivoted levers and being provided with a tongue fitted in the slot of said casing, and means for rotating 75 one of said disks, substantially as set forth.

80 13. A counting-machine having in combination a casing provided with a slot in the end thereof, a cam having a tongue fitted in said slot, a series of digit-disks having pivoted 85 levers, a pin passing through said disks and cam, said cam being arranged to engage with one of said levers, and means for imparting rotation to one of said disks and communicating the movement of the lever carried 90 thereby to the others of said disk, substantially as set forth.

95 14. A counting-machine having in combination a casing provided with a slot in the end thereof, a cam having a tongue fitted in 100 said slot and being provided with the lip 47, a series of digit-disks arranged in said casing, a pin passing through said disks and cam, means for rotating one of said disks and means for imparting such rotation to the 105 remaining disks, substantially as set forth.

100 15. A counting-machine having in combination a casing, a series of digit-disks mounted in said casing and being provided with teeth or lugs, means for imparting the movement 110 of one of said disks to the other, a pawl located between the end of said casing and one of said disks, a lever pivoted on the outside of said casing and having an inwardly-projecting pin, said casing being provided with 115 a curved slot through which said pin passes and said pawl being pivoted upon said pin, and a hood arranged over said slot, substantially as set forth.

115 16. A counting-machine having in combination a casing, a series of digit-disks mounted in said casing and having teeth or lugs, a pawl engaging with said teeth or lugs for rotating said disks, means for imparting the movement of one of said disks to the others, 125 the lever 24 pivoted to the end of said casing and having the inwardly-projecting pin 34, the rod 35 pivoted on said pin between said lever 24 and casing, a spring shouldered upon said rod and the perforated ear 38 through 130 which said rod passes and upon which said spring is supported, substantially as set forth.

17. A counting-machine having in combination a casing, a series of digit-disks mounted

therein and provided with teeth or lugs, holding-dogs engaging with said teeth or lugs, springs arranged under said holding-dogs, the plate 18 located in the bottom of the casting and being provided with apertures in which said springs rest, said plate being also provided with the lugs 19 engaging in said casing, and the removable face-plate 20 holding said plate 18 in place, substantially as set forth.

18. A counting-machine having in combination a pawl for actuating the counting mechanism, a pivoted lever having one end pivoted to said pawl for operating it, a pivot 15 at the other end of said lever, a rod secured to said last pivot, a perforated ear through which said rod passes, a spring shouldered on said rod and bearing against said ear, the pivot carried by said lever being arranged to 20 one side of a straight line extending between said ear and the axis of said lever, an arm connected with said lever and adapted to

force the said pivot carried thereby to a position between said ear and axis, whereby the effect of the leverage upon said spring will 25 be increased substantially in proportion to the increasing resistance of the spring, substantially as set forth.

19. A counting-machine having in combination a digit-disk provided on one side with 30 the lugs 40 having the bore 40^b, a lever arranged between said lugs for the purpose specified, a pin passing through said lugs 40 and lever, the pintle 2 passing through said disk and holding said pin from movement in 35 one direction and the pin 40^c passing through one of said lugs at the other end of said pin for holding the latter against movement in the opposite direction, substantially as set forth.

ROBERT MIEHLE.
